UNITED STATES PATENT OFFICE.

JACOB L. MOORE, OF BUTLER, PENNSYLVANIA.

DESIGN FOR A BEDSTEAD.

41,640.

Specification for Design.

Patented Aug. 1, 1911.

Application filed February 8, 1911. Serial No. 607,435. Term of patent 14 years.

To all whom it may concern:

Be it known that I, JACOB L. MOORE, a citizen of the United States, residing at Butler, in the county of Butler and State of Pennsylvania, have invented a new, original, and ornamental Design for a Bedstead, of which the following is a specification, reference being had to the accompanying drawing, forming a part hereof.

This invention has for its object to provide a novel and ornamental design for a bedstead.

The accompanying drawing illustrating my design shows a bedstead embodying the same in perspective view.

The novelty of the design consists principally in the relative arrangement of the panels and bed posts whereby a free space is left between the latter and end-framing pieces of the panels in the middle of each of which a member is inserted which is parallel with the bed posts and the end-framing pieces of the panels.

I claim:

The ornamental design for a bedstead as shown and described.

JACOB L. MOORE.
